RAIL AND FLANGE LUBRICATOR

Application filed October 17, 1927. Serial No. 226,804.

My invention pertains to improvements in rail and wheel flange lubricating appliances, particularly adapted to the problem of applying lubrication to the vertical contacting

5 areas of wheel and rail on curved tracks of railroads. It being understood that the invention contemplates the application of the lubricant in such manner that it will become effective between the vertical contacting 10 surface of the fixed rail and the flange of the moving wheel; and to this end the primary application of the lubricant may be to either the vertical side of the rail, the vertical projecting flange of the wheel, or to 15 both of these surfaces, as more particularly explained hereafter.

According to accepted railroad practices, the flanges of car wheels depend below the surface of the rail and lie along the inner face thereof. When negotiating curves, it follows that the inner face of the outside curved rail bears the heavy frictional grinding of the flanges of the car wheels, and it is this 20 zone of contact that requires lubrication.

25 The problem of effectively applying lubrication to this contacting zone has been found to be a most difficult one, and among the objects of my invention are:—

a—The provision of an inexpensive and 30 simple lubricating device that is durable, and will require the minimum of attention.

b—The provision of a device that will apply the lubricant in proper amount and only 35 on the surfaces requiring lubrication, without splashing the traction surfaces of the rail or driving wheels.

c—The provision of a device which is operative by contact with car wheels at the 40 moment of their passing.

d—The provision of a device wherein the lubricant and the applying mechanism are protected from the weather and from foreign substances incident to the operation of the 45 train, such as, cinders, rail-sending, etc.

e—The provision of a device designed to 50 operate effectively in freezing weather, and especially against accretions of snow and ice, or like obstructions and accumulations.

55 With the above and other objects in view, this invention comprises the novel construc-

tion and combination of parts more particularly set forth herein, illustrated by the preferred embodiment in the drawings, and particularly claimed.

In brief, my invention comprises a stationary reservoir for the lubricant, located adjacent the rail to be treated; a dauber contained within the reservoir and normally submerged in the lubricant and well below the top of the rail; a reservoir cover to protect the body of lubricant; means operated by the passage of a car wheel over an operating lever system, or the like, whereby the dauber is caused to emerge from the reservoir and smear the vertical flange of the wheel, the 60 vertical face of the rail, or both—to suit the particular desires of the designer of the device. The dauber automatically reseats itself after the passage of the train, and the entire operating gear rests itself, ready for the 65 next train.

Additional details and variations of construction are more particularly developed by the accompanying drawings, in which

70 Figure 1 shows a top view of one form of my invention; the hinge of the cover being remote from the rail. Two dauber operating levers are shown, and a portion of the cover is broken away to show the mechanism below.

75 Figure 2 is a cross section through (2—2) of Figure 1. The dauber and cover as shown in full section lines representing the position when the device is smearing lubricant when operated upon by the car wheel, shown in 80 broken lines. The dauber and cover as shown in broken lines indicates the inactive position when not being traversed by a car wheel.

85 Figure 3 shows a longitudinal sectional elevation through a portion of the device, as through a plane (3—3) of Figure 2, looking toward the rail. One of a series of operating levers is indicated. The lever, dauber, and cover plate shown in solid lines indicate the 90 operative position of the device, while the broken lines indicate the inoperative position.

95 Figure 4 is a cross section through a reservoir such as that of Figure 2, but showing 100

a different type of dauber operating lever, fulcrumed to swing transverse of the length of the reservoir. Full lines indicate the operative position of the dauber and its motivating mechanism, while the inoperative position is shown in broken lines.

Figure 5 is a cross section similar to Figure 4 illustrating another system of dauber operating mechanism. The full lines indicating the operative position of the dauber, while broken lines indicate the inoperative position.

As the operation of the device and its preferred mechanism is made obvious by the drawings, only a brief narrative will be given. In the several views of the drawings similar numerals of reference indicate corresponding parts.

The reservoir 10 is suitably affixed along the rail to be treated and preferably comprises an oil-tight elongated trough covered with a weather proof hinged cover 11, preferably hinged at 12 remote from the rail, whereby the free edge may swing under the impact of the flange of the passing car wheel and operate the dauber through suitable associated mechanism.

The long free edge of the cover extends toward the rail as close as is possible to leave a clearance for the rise and fall of the dauber as it does its work. The free edge of this cover is close enough to the rail to be traversed by the flange of the car wheel and the system thereby operated. The level of the liquid lubricant is indicated as 13.

The dauber 14 is preferably of an oil retaining compound, such as felt suitably reinforced by a metallic backing, or the like. This dauber extends longitudinally of the rail edge and is suitably affixed to operating levers 15, and otherwise stiffened by a stout backing strip 16, or the like. These levers, in the preferred embodiment, are of the bell crank type with a fulcrum as at 17 (Figs. 1-2-3-4).

The system in repose contemplates that the primary dauber operating element, as shown the free edge of the cover 11, shall be raised within the path of the car wheel flange and so balanced that it will return to this position when the depressing influence of the car wheel has passed. To effect this, the dauber and its operating mechanism associated with the cover, may be so balanced that the cover is held up in wheel-contacting position by the gravity balance of the system.

In Figure 2, a cover raising spring 18 is added as a positive means for insuring that this cover will be normally kept raised, and a limit stop 19 (Figures 1 and 3) is provided to properly position the raised cover 11.

A stout metallic strip 20 (see Figures 1 and 2) may be added to the free edge of the cover in the path of contact of the traversing wheel flange for the purpose of strengthening the

cover against shock and absorbing wear. To prevent undue splash of lubricant when the dauber is suddenly raised by the wheel impact, a splash guard or dampener 21 (see Figure 2), may be added along and overhanging the free edge of the cover.

This splash guard may become an important feature in cases where relatively light lubricants are used in certain localities and at certain seasons of the year, for it will definitely prevent splashing of the rail surface, thus avoiding loss of tractive effort of the locomotive drivers.

The type of dauber mechanism illustrated in Figures 1, 2 and 3, provides for a parallel motion of the rising dauber. The dauber and its reservoir may be of any desired length to meet the local requirements and the grade of lubricant preferred. Where the parallel motion is used, it is preferred that there be a plurality of operating levers 15, and these are practically simultaneous in their operations in raising the dauber, for the reason that the entire stiff cover 11 is depressed at the instant that a traversing car wheel meets contact with its edge. A boss 22 may be fashioned on the under side of the cover 11 as a means for depressing an end of lever 15 (Figures 2 and 3), and the dauber connection at the other end of the lever may be any suitable pivot, as 23.

Where it is desired to place the smear mainly upon the wheel flange, the arrangement of Figure 4 will work to advantage; for in this variation of leverage, the lever 15 with its dauber fixed at a free end, is arranged to swing the dauber through an arc whose center is the fulcrum point of the lever. This fulcrum point has its axis parallel to the length of the dauber strip, whereby the swing of the dauber is transverse of the length of reservoir, clearing the side of the rail where desired, and causing the exposed dauber edge to smear the vertical wheel flange, as shown.

In Figure 5 the leverage system to attain an accurate swing of the dauber strip, comprises, a primary lever 15 fulcrumed at 26 remote from the rail, and actuated by a short bell crank lever 27 fulcrumed at 28. This short lever is actuated by a push rod 29 suitably attached to the cover 11 at one end and is pivoted at 30 to an end of 27. A stud 31 at the other end of lever 27 actuates the dauber lever 15 by sliding contact, in the manner clearly indicated by the drawings.

The reservoir 10 is secured to the cross ties by a suitable clip 32 in properly spaced relationship to the rail, whereby the clearance between the dauber strip and the rail side is definitely fixed to best advantage. The reservoir may be cross-bolted to the rail if desired.

In the several views of the drawings, it will be noted that the vertical flange of the car wheel is shown out of contact with the ver-

tical face of the rail 25 and the dauber is shown entering within this clearance to accomplish its work. The clearance shown is accounted for by the provision of a deflecting 5 or guard rail placed just inside of the rail opposite the one to be smeared, and, of course, opposite the position of the reservoir 11, whereby the axle supporting the opposed car 10 wheels will be caused to temporarily lurch away from the rail to be smeared, thus causing the wheel and its vertical flange to assume the clearance position desired and shown. (This is a well known railroad expedient, and no drawing is appended for the 15 reason that the feature is not an element of my invention.)

In fact, the clearance between vertical flange and rail is not essential to this invention. Where it is desired to permit the normal 20 contact between rail surface and vertical flange of wheel at the point where lubrication is to be applied, the dauber throw could be restricted to merely make contact at the point where wheel flange and rail side meet, 25 and the lubricant would find its way between the so contacting surfaces. (This is obvious, and the variation is not deemed of importance in the drawings.)

The best location for the lubricating device 30 is at the end of the straight-away, near the point of tangency of the curve to be treated. Of course additional lubricators may be placed within the curve, but this is not necessary in view of the fact that tests of this 35 device on one of the larger railroads disclose the rather astonishing fact that the lubricant extends for several miles along the side of the rail beyond its point of application. The flanges of the wheels retain enough lubricant 40 to cause this extensive distribution.

A particular feature of this invention is the very important fact that the contrivance will be effective in freezing weather and against the accumulation of ice and snow that will 45 necessarily lodge upon the cover. By reference to Figures 2, 4 and 5 it is noted that the cover reposing in the "up" position is sloped away from the rail top and its free edge extends very close thereto. Thus, there 50 is a tendency for obstructions to slide off the cover. Where, as is often the case, the entire cover will be coated with snow and ice in its "up" position, the sudden impact of a wheel thereon will drive the cover edge down as the 55 dauber strip comes up between it and the rail. This impact and drop of the cover will break the seal of ice or snow that may have formed between the free edge of the cover and the paralleling side face of the rail, 60 whereby the dauber will find a free space within which to rise and smear the objective surface.

It is also noted that the entire actuating mechanism is effectively sealed from injury; 65 deterioration by reason of weather conditions;

from invasion into the lubricant of foreign substances; that the system is self-lubricating by having its principal mechanism emersed in the body of the lubricant; and that no vital moving parts are so exposed to the weather that they may become frozen up or otherwise rendered inoperative.

The mechanism may be examined at will by merely hinging the cover, as indicated; and filling may be likewise effected.

While the preferred embodiment of this device necessarily discloses a limited choice of mechanisms for carrying it into successful practice, it will be understood that the invention is not to be thus restricted, but is to be given the scope to which it is entitled in the art as defined by the appended claims.

I claim:

1. A rail and wheel flange lubricator, comprising; a reservoir for lubricant adjacent a rail; a dauber normally inactive within the reservoir out of contact with an objective surface to be lubricated; dauber operating means comprising means responsive to the contact of a flanged car wheel traversing said adjacent rail whereby the dauber is caused to lubricate the said car wheel flange; and means for restoring said dauber to the normally inactive position when the car wheel has passed.

2. A rail and wheel flange lubricator, comprising; a reservoir for lubricant adjacent a rail; a dauber normally inactive below the top of the reservoir and below the level of an objective surface to be lubricated; dauber operating means comprising means responsive to the contact of a flanged car wheel traversing said adjacent rail whereby the dauber is caused to rise above the reservoir and contact with the passing car wheel flange; and means for restoring the dauber to the normally inactive position when the car wheel has passed.

3. A rail and wheel flange lubricator, comprising; a reservoir for lubricant adjacent a rail; a dauber normally below the point of contact with an objective surface to be lubricated and housed within the reservoir; dauber operating means responsive to the contact of a flanged car wheel traversing said adjacent rail whereby during such contact the dauber is caused to rise against the said traversing car wheel flange and effect lubrication thereof.

4. A rail and wheel flange lubricator, comprising; a reservoir for lubricant adjacent a rail; a dauber normally submerged within a lubricant contained in said reservoir and entirely housed thereby; dauber operating means responsive to the contact of a car wheel traversing said adjacent rail whereby during such contact the dauber is caused to emerge from said lubricant and rise to contact with said traversing car wheel and effect lubrication thereof; and means for returning said dauber within the lubricant when the car wheel has passed.

5. A rail and wheel flange lubricator, comprising; a reservoir for lubricant adjacent a rail; a dauber normally housed within the reservoir and submerged within the lubricant; dauber operating means responsive to the contact of a car wheel traversing said rail whereby the dauber is caused to contact with and lubricate the objective car wheel; and a splash guard adapted to control the excess lubricant upon the dauber.
6. A rail and wheel flange lubricator, comprising; a reservoir for lubricant adjacent a rail; an elongated dauber disposed in parallelism with the rail and normally inactive within the body of the reservoir and submerged within the lubricant; a hinged cover protecting the reservoir and normally in position to be struck and depressed by a wheel passing on said rail; dauber operating means associated with said cover whereby the dauber is caused to rise and lubricate the objective car wheel during its passage across said cover and return to its inactive position when the said wheel has passed.
7. A device of the character described, comprising; a reservoir for lubricant adjacent a rail; a dauber mechanism including a dauber associated with the reservoir; means for causing the dauber to normally lie within the confines of said reservoir and in contact with a lubricant therein; dauber operating means responsive to the contact of a car wheel passing on said rail whereby the dauber is positively raised and pressed against a portion of the periphery of said wheel throughout some period of the contact of said wheel with the said dauber operating means whereby a lubricant is applied thereto; and means for causing the dauber to return to an inoperative position when the car wheel has released said dauber operating means.
8. A device of the character described, comprising; a reservoir for lubricant adjacent a rail; a dauber within the reservoir and normally immersed within a lubricant therein; means associated with said dauber and interposed within the path of the periphery of a car wheel traveling said rail whereby the dauber is raised and positively applied to a portion of the said wheel periphery at such time that the wheel is operatively engaged with the means for raising the dauber, and means for lowering the dauber within the reservoir when the said wheel has released the said dauber operating means.

In testimony whereof I affix my signature.
MARK W. ROE.
